(57) **CLAIM**

The ornamental design for a communication device, as shown and described.

DESCRIPTION

FIG. 1 is a perspective view of a communication device showing our new design.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

The broken lines shown in FIGS. 1-7 that are immediately adjacent to the shaded areas represent the bound of the claimed design, while all other broken lines are directed to environment and are for illustrative purposes only; the broken lines form no part of the claim design.
